UNITED STATES PATENT OFFICE

169,871

ILLUMINABLE SHADOW BOX OR SIMILAR
ARTICLEHarold L. Speer and Marcherette K. Speer,
Santa Cruz, Calif.

Application November 17, 1952, Serial No. 22,320

Term of patent 7 years

(Cl. D29—20)

To all whom it may concern:

Be it known that we, Harold L. Speer and Marcherette K. Speer, citizens of the United States, residing at Santa Cruz, county of Santa Cruz, State of California, have invented a new, original, and ornamental Design for an Illuminable Shadow Box or Similar Article, of which the following is a specification, reference being had to the accompanying drawing, forming part thereof, in which:

Figure 1 is a perspective of an illuminable shadow box or similar article, showing our new design; and

Figure 2 is an elevational view thereof, both ends being identical with one another.

We claim:
The ornamental design for an illuminable shadow box or similar article, substantially as shown.

HAROLD L. SPEER.
MARCHERETTE K. SPEER.
